DESIGN FOR A VENTILATOR FOR MOTOR VEHICLE WINDOW

Joseph J. Foley, Chicago, Ill.

Application May 26, 1933. Serial No. 48,219

Term of patent 14 years

To all whom it may concern:

Be it known that I, JOSEPH J. FOLEY, a citizen of the United States, residing at Chicago, in the county of Cook and State of Illinois, have invented a new, original, and ornamental Design for Ventilator for Motor Vehicle Window, of which the following is a specification, reference being had to the accompanying drawing, forming a part thereof.

Figure 1 is a perspective view of a ventilator for an automobile window showing my new design;

Fig. 2 is a side elevation thereof; Fig. 3 is a top plan view thereof; and Fig. 4 is a section on the line 4—4 of Fig. 1. The construction shown comprises a three-sided frame in which is mounted a transparent pane.

I claim:

The ornamental design for a ventilator for motor vehicle window substantially as shown and described.

J. J. FOLEY.
